UNITED STATES PATENT OFFICE.

EMIL HAEFELY, OF BASEL, SWITZERLAND.

WINDING-MACHINE FOR THE MANUFACTURE OF HOLLOW INSULATING-CYLINDERS FOR ELECTROTECHNICAL PURPOSES.

1,328,792.

Specification of Letters Patent. Patented Jan. 20, 1920.

Application filed October 25, 1919. Serial No. 333,344.

To all whom it may concern:

Be it known that I, EMIL HAEFELY, a citizen of the Swiss Republic, and resident of Basel, Switzerland, have invented new and 5 useful Improvements in Winding-Machines for the Manufacture of Hollow Insulating Cylinders for Electrotechnical Purposes, of which the following is a full, clear and exact specification.

10 This invention relates to a winding machine for the manufacture of hollow insulating cylinders for electro-technical purposes from a band of fibrous material, which is wound with an adhesive substance upon 15 a winding roller between heating cylinders and a pressure cylinder.

A machine of this kind must be so constructed as to be equally suitable for the manufacture of insulating hollow cylinders 20 of any size, from the smallest to the largest. For small cylinders a small winding roller is required for the winding, and for large cylinders a large one. According to the diameter of this winding roller it is necessary 25 on the one hand to arrange for the adjustment of the relative initial distances of the heating cylinders, since care must be taken that for both small and large winding rollers the direction of pressure at the 30 points of contact of the fabric with the heating cylinders remains approximately the same, so that in all cases the same effective pressure is applied, which pressure is equally homogeneous with both large and small 35 hollow insulating cylinders. On the other hand, the employment of a small or large winding roller requires a drive which provides for the spindle of the winding roller being shifted according to the diameter of the 40 winding roller.

According to the invention these conditions are fulfilled by making the heating cylinders adjustable in each case, as regards their relative distance to suit the sizes of the 45 winding rollers to be used, and the drive of the winding rollers, is effected by two vertical shafts with worms, in which engage worm-wheels connected with the winding rollers and of a diameter such that the teeth 50 laterally engage with the worms. This machine thus forms a kind of universal winding machine, on which small or large hollow insulating cylinders can be made as required.

In the accompanying drawing:

55 Figure 1 is a side elevation showing the

construction of the winding machine when a small winding roller is used, and

Fig. 2 is a similar view showing the construction when a large winding roller is used.

⁶⁰
a, b are the heating cylinders on which rests the winding roller *c* or *c'*. In Fig. 1, in which a small winding roller *c* is being used, the two heating cylinders *a, b* are adjusted near together. In Fig. 2 in which a ⁶⁵ large winding roller *c'* is used, the heating cylinders are placed correspondingly far apart. This adjustment of the heating cylinders *a, b* is effected by means of sliding carriers *d*, which move along bars *e*, and can ⁷⁰ be adjusted by blocks *f* engaging in holes in the bars. The bars *e* can be adjusted longitudinally in the cheeks *g* upon the side of the frame, by means of a worm and screw gear *h*, so that when the adjustment of the ⁷⁵ heating cylinders at their proper distance apart has been effected, the winding roller can be placed exactly vertically under the pressure cylinder *i*.

For driving the winding roller *c* or *c'* to ⁸⁰ wind on the band of fibrous material or paper *x*, two vertical driving shafts *k* (placed one behind the other in the drawing) are provided on the frame of the machine, on which is a worm *m* adjustable by ⁸⁵ a groove and key, and the position of which on the height of the spindle of the winding roller in use can be adjusted by convenient means.

The spindle of the winding roller is provided at each end with a worm-wheel *n* of a diameter suitable to that of the roller, and this engages laterally with the teeth of the corresponding worm. This method of driving the winding roller allows of the easy insertion and removal of the latter.

The application and removal of the drive is effected by shifting the bars *e* by means of the screw spindle gear *h*.

Instead of making the worms *m* adjustable vertically, they may occupy the whole of the height of the spindles *k*.

What I claim is:

1. A winding machine for the manufacture of hollow insulating cylinders for electro-technical purposes, from a band of fibrous material supplied with an agglutinant, comprising two heating cylinders, a rotary winding roller between them to wind the band upon it, a pressure cylinder to ex- ¹⁰⁵ ¹¹⁰

- ert thereon the necessary pressure for the winding operation, means for adjusting the relative distance apart of the heating cylinders according to the size of the winding 5 roller to be employed, vertical driving shafts, worms thereon, worm-wheels carried by the winding roller, and means for laterally engaging said worm-wheels into their respective worms, substantially as described.
- 10 2. A winding machine for the manufacture of hollow insulating cylinders for electro-technical purposes, from a band of fibrous material supplied with an agglutinant, comprising two heating cylinders, a rotary 15 winding roller between them to wind the band upon it, a pressure cylinder to exert thereon the necessary pressure for the winding operation, means for adjusting the rela-

tive distance apart of the heating cylinders according to the size of the winding roller 20 to be employed, vertical driving shafts, worms thereon, worm-wheels carried by the winding roller, and means for shifting the adjusted heating cylinders together with the winding roller as a whole for laterally en- 25 gaging or disengaging said worm-wheels with respect to their respective worms, sub- stantially as described.

In witness whereof I have hereunto signed my name this 30th day of September 1919, 30 in the presence of two subscribing witnesses.

EMIL HAEFELY.
